UNITED STATES PATENT OFFICE.

HENRY J. P. WHIPPLE, OF NEW HAVEN, CONNECTICUT.

KNOB ATTACHMENT.

SPECIFICATION forming part of Letters Patent No. 601,724, dated April 5, 1898.

Application filed June 25, 1897. Serial No. 642,246. (No model.)

To all whom it may concern:

Be it known that I, HENRY J. P. WHIPPLE, a citizen of the United States, residing at New Haven, in the county of New Haven and State 5 of Connecticut, have invented certain new and useful Improvements in Knob Attachments; and I do hereby declare the following to be a full, clear, and exact description of the invention, such as will enable others skilled in the 10 art to which it appertains to make and use the same.

My invention relates to an improvement in knob attachments, and has for its object to provide simple but effective means for securing 15 an accurate adjustment of the parts to prevent end thrust of the knob-spindle regardless of the thickness of the door to which it is applied, which means can be operated quickly and conveniently to secure the desired 20 adjustment and can be manufactured at a considerably less cost than the various forms of means heretofore employed for this purpose.

To this end my invention consists in the 25 knob attaching and adjusting means herein-after fully described, and particularly pointed out in the claims.

Referring to the drawings, in which like numerals designate like parts in the several 30 views, Figure 1 is a side view, partly in longitudinal section, of a pair of knobs applied to a door in accordance with my invention. Fig. 2 is a longitudinal section showing the adjusting means devised by me at one end of 35 the knob-spindle. Fig. 3 is a side view of the adjusting-sleeve forming part of such adjusting means. Fig. 4 is an end view of said sleeve. Fig. 5 is a plan view of a slightly-modified form of the locking-detent. Fig. 6 40 is a side view of the detent shown in Fig. 5. Fig. 7 is a side view of the form of adjusting-sleeve used with the detent shown in Figs. 5 and 6.

The numeral 1 designates a portion of a 45 door which is bored, as usual, to permit the knob-spindle 2 to be passed through it. Said spindle 2 is or may be of the usual rectangular form in cross-section, containing a series of notches near one end to receive the latch 50 3 on the neck of the knob 4 to enable said knob to be adjustably secured upon the spin-

dle in the usual manner. It is to compensate for the inaccuracy of the approximate adjustment secured by such notches and latch or of the various other forms of adjustable connection at that end of the knob-spindle that the supplementary adjusting means of the class to which my invention appertains is applied to the knob connection at the opposite end of the spindle. 55

In the practice of my invention I locate upon the neck 5 of the knob 6 an adjusting-sleeve 7, which bears at its inner end against the bottom of the socket 8 in the rose 9, as shown in Fig. 2, and is engaged at its outer 60 end by a depressible detent on said neck and provide means, located either upon said outer end of said sleeve or upon said detent, for securing longitudinal adjustment of the sleeve upon the neck. 70

As shown in Figs. 1 to 4, inclusive, the sleeve 7 is provided at its outer end with a series of depressions or notches 10 of a progressively-increasing depth, and the detent 12 is located within a recess 13 in the outer 75 surface of the neck, it having a stem or shank 14, which enters a socket 15, extending transversely into the neck and spindle, a spring 16 between said shank or stem and the bottom of said socket serving to exert outward 80 pressure against the detent. Said detent is provided with a rounded shoulder 17 at its inner end, which is adapted to fill either of the notches 10 in the sleeve when caused to register therewith by turning the sleeve, 85 while at its extreme end it projects within the sleeve, as shown in Fig. 2, whereby the sleeve is caused to limit its outward or radial movement and prevent its accidental disengagement from the neck. I also prefer to provide 90 against accidental displacement of the sleeve from the neck by forming the neck with a circumferential groove or depression 18 of sufficient width to permit of the required longitudinal movement of the sleeve thereon 95 and by providing the sleeve with an internal projection 19 to enter such groove or depression, it being led into the latter through a guiding-notch 20, leading from the groove 18 to the inner end of the neck, as shown in Fig. 100 2. The usual rivet 21 secures the neck 5 of knob 6 to the spindle 2.

In assembling the parts just described the end of the spindle 2 is inserted within the neck 5 and riveted. The stem 14 of detent 12 is inserted within the socket 15, spring 16 having first been dropped into said socket. 5 The detent is depressed within recess 13 of the neck until its outer face is flush with the circumferential surface of the latter and is held in such position by the finger or thumb 10 of one hand, and with the other hand the operator applies the sleeve 7 to the spindle, passes its projection 19 through the notch 20 into the groove or depression 18, thereby causing its outer end to overlap the inner 15 end of the depressed detent, and imparts to it a slight turning movement to move the projection 19 out of alinement with the said notch 20. When thus assembled, the parts are retained in their operative positions with- 20 out danger of being displaced and lost either in packing and shipment or handling the same previous to their being applied to a door.

In applying the knobs to a door the spindle 2, having the knob 6 secured thereto, as 25 just described, is thrust through the hole in the door and into the neck of knob 4, and latch 3 is lowered into one of the notches in the spindle. The spindle is then moved lon- 30 gitudinally, by grasping knob 6, to cause the latch 3 of knob 4 to enter within the flange 22 of rose 23, as shown in Fig. 1, and sleeve 7 is thrust against the bottom of the socket 8 in rose 9 and is revolved to move into register with detent 12 that one of its end de- 35 pressions or notches 10 which by engaging the shoulder 17 on the detent will lock it in such position. The progressively-increasing depth of said notches or depressions 10 enables a 40 very accurate adjustment to be secured by said detent and sleeve to prevent any end thrust of the spindle in the beginning and to compensate for any which may develop by wear of the parts.

45 To remove the knobs from the door, it is necessary simply to depress the detent, slide the adjusting-sleeve outwardly upon the neck 5, thrust the spindle in the opposite direction to uncover the latch 3, raise said latch, 50 and withdraw the knob 4.

55 It will be observed that both operations of applying the knobs to and removing them from a door can be performed very quickly and conveniently and without the use of tools of any sort.

In Figs. 5, 6, and 7 I have shown a slightly-modified form of the invention, in which the detent 24 bears upon its outer face a series of shoulders 27, located at progressively-in- 60 creasing distances from its inner end, as shown, and the adjusting-sleeve 25 has a single notch or recess 26 in its outer edge to receive the detent, and thereby prevent the sleeve from turning on the neck. The de- 65 tent 24 is supported upon the neck 5 in the same manner as the detent 12, and the adjustment of the position of the sleeve upon

the neck is secured by varying the particular shoulder upon said detent which engages the end of the sleeve.

70 As the first-described form of the invention secures a wider range of adjustment for the sleeve than is possible with the last-described form, unless the size of the detent be unduly increased, I prefer to utilize such form in most cases.

80 Attention is called to the fact that in both of the forms of the invention herein shown I entirely avoid the use of screw-threads upon either the knob, neck, or the sleeve, and thereby effect a material saving in the cost of manufacture over previous devices of this character, besides being enabled to use very thin sheet metal for the adjusting-sleeve, thus lessening the cost of material.

85 The adjusting means herein described present a pleasing and ornamental appearance when applied to the door.

90 It is obvious that various other modifications in the details of construction herein shown and described can be made within the spirit of the invention.

95 Having thus fully described my invention, what I claim, and desire to secure by Letters Patent, is—

1. The combination with a door-knob neck, of a sleeve mounted upon said neck and adapted for a free sliding movement longitudinally of the latter, and a detent upon said neck adapted to make contact with said sleeve to limit its movement, one of said two contacting parts being provided with a plurality of contact-surfaces located at varying distances from the inner end of the neck, to hold the sleeve in different positions upon the latter, substantially as described.

2. The combination with a door-knob neck, of a sleeve mounted upon said neck and projecting at its inner end beyond the end of the latter, said sleeve being free to move longitudinally upon the neck and being provided with a plurality of engaging surfaces located at varying distances from its inner end, and a detent upon the neck adapted to engage said surfaces on the sleeve interchangeably, substantially as and for the purpose described.

3. The combination with the neck of a door-knob, of a sleeve loosely mounted upon said neck and projecting at its inner end beyond the end of the latter, said sleeve having in its outer end a series of notches or depressions of a progressively-varying depth, and a spring-actuated detent radially movable upon the neck and adapted, in its outermost position, to engage the notches or depressions in said sleeve, substantially as described.

4. The combination with the neck of a door-knob having located thereon a radially-movable, spring-actuated detent the outer face of which is shouldered as described, of a sleeve loosely mounted upon said neck and overlapping at its outer end said detent, said sleeve having in its said outer end a series of notches or depressions of varying depth to receive the

shoulder on the detent, substantially as set forth.

5. The combination with a door-knob neck provided with a circumferential groove or recess and with a longitudinal notch or recess leading therefrom to the end of said neck, of a detent having a stem or shank which enters a transverse socket in said neck and having its outer face provided with a shoulder as described, a spring located in said socket and exerting outward pressure against the stem of said detent, and a sleeve loosely mounted upon said neck and overlapping said detent at one end, said sleeve being provided with 10 an internal projection to enter the circumferential groove in the neck and having at the end thereof which overlaps said detent a se-

ries of notches or depressions of varying depth to receive the shoulder on the latter, substantially as described.

6. The combination with the knob-neck 5 having the recess 13 and socket 15, of the detent 12 having the stem 14 which enters said socket and the shoulder 17, spring 16, and sleeve 7 projecting at its inner end beyond 25 the end of said neck and having in its outer end the series of notches 10 of varying depth, substantially as described.

In testimony whereof I affix my signature in presence of two witnesses.

HENRY J. P. WHIPPLE.
